UNITED STATES PATENT OFFICE.

DANIEL B. COATES, OF PAYETTE, IDAHO.

FARM GATE AND GARAGE DOOR.

Application filed November 5, 1927. Serial No. 231,301.

This invention has reference to gate construction and aims to provide novel means whereby gates may be operated by the weight of a vehicle moving towards the gate, thereby eliminating the necessity of the operator of the vehicle alighting from the vehicle to manually operate the gates.

An important object of the invention is to provide an operating means so constructed 10 that a vehicle moving on one side of the gate will act to open the gate while the vehicle moving from the gate will operate a mechanism to close the gate.

With the foregoing and other objects in view which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

Referring to the drawings:

25 Figure 1 is a perspective view illustrating a gate and operating mechanism constructed in accordance with the invention.

Figure 2 is a perspective view and illustrating one of the gate sections in its open 30 position.

Figure 3 is a sectional view taken on line 3—3 of Figure 2.

Figure 4 is a sectional view taken on line 4—4 of Figure 1.

35 Referring to the drawings in detail, the reference character 5 designates gate posts at the opposite sides of the roadway, and as shown, one of these gate posts is substantially long and extends an appreciable distance above the other gate post as at 6.

These posts 5 are connected by means of the bar 7 which not only acts as a means for holding the posts in proper spaced relation with each other, but at the same time 45 provides means for supporting the actuating lever indicated by the numeral 8 and to be hereinafter more fully described.

The gate includes gate sections of the sliding type and are indicated generally by the 50 numeral 9, each gate section including uprights 10 that are connected at their upper ends by means of the bar 11, there being provided brackets 12 secured to the bar and uprights which brackets support the rollers 13 that move along the pivoted track sections 14.

These track sections 14 are pivoted to the posts 5 at 15 or at points substantially intermediate the ends thereof, the track sections being formed preferably of angle bar material and provided with outstanding flanges 60 over which the rollers operate. Stops 14' are provided at the ends of the track sections to limit the movement of the gate sections thereover.

Thus it will be seen that it is the purpose 65 of the invention to move the track sections to elevate one of the respective ends thereof to cause the gate sections to gravitate to the lower ends of the track section to either open or close the gate.

70 At the inner ends of the track sections 14 are rods 17 that have their upper extremities connected with one end of the actuating lever 8 as at 18, the opposite end of the lever having connection with the control 75 cables that transmit movement from the road operating lever or treadle, to the actuated lever 8 to operate the gate sections.

These cables are arranged in pairs at 80 opposite sides of the gate, there being provided a cable 19 that connects with the upper edge of the actuated lever so that when this cable 19 is pulled, the actuated lever will be elevated at its outer end, lowering the inner end of the actuated lever to cause the 85 track sections to tilt inwardly causing the gates to close.

As shown, each cable 19 operates over a pulley 20 from where it passes over the pulley 21 and over the pulley 22, from where 90 it passes downwardly over pulley 23 and connects with one side of the segment 24 associated therewith.

95 Each cable 25 connects with the lower side of the actuating lever as shown by Figure 1 and passes over the pulley 26 from where it passes rearwardly over the pulley 27 and downwardly over the pulley 28 where it connects with the segment 24. It will of course be obvious that this mechanism is duplicated on the opposite side of the gate, there being provided control cables and an actuating means identical with that described, so that the gates may be operated from either side.

100 The treadle at each side of the gate is indicated at 29 and is mounted on a shaft 30 which operates in bearings 31 anchored in the road bed, the treadle being so positioned that a vehicle may readily pass there- 110

over, the weight of the vehicle acting to force the treadle 29 downwardly to operate the cables as described.

Connected with each shaft 30 is a vertical lever 32 that operates between the bar 33 and segment associated therewith. The bar 33 has right angled ends 33' that are secured to the segment associated therewith to hold the bar in spaced relation with the segment. It will be seen that due to this construction, the lever 32 will contact with one of the ends 33' to move the segment.

Connected with each lever 32 is a cable 34 that operates over the pulleys 35 and 36, the free end of the cable being supplied with a weight 37 and a coiled spring 38 to normally hold the lever and treadle 29 in their upright positions. A frame work embodying posts 39 and 40 act as supports for the various pulleys and operating mechanism.

Thus it will be seen that should a vehicle pass over a treadle 29 at one side of the gate, the treadle will be moved downwardly causing a pull to be exerted on the cable 25 which in turn will act to lower the outer extremity of the actuating lever.

As the outer end of the actuating lever is lowered, the inner end thereof is elevated, causing the inner ends of the track sections 14 to be elevated and resulting in an outward sliding movement being directed to the gate sections for opening the gates.

As the vehicle passes through the opening, the vehicle will contact with the treadle 29 at the opposite side of the gate, which will operate to elevate the outer end of the actuating lever and causing a downward movement to be imparted to the inner ends of

the track sections 14, with the result that the gate sections will gravitate to their closed positions.

I claim:

1. A gate construction including gate posts supported at opposite sides of a roadway, pivoted track sections mounted on the gate posts, gate sections movable over the track sections and adapted to gravitate to the lower ends of the track sections when the track sections are tilted, an actuating lever supported above the track sections, rods connecting one end of the actuating lever and the inner ends of the track sections, cables connected with the actuating lever, and vehicle controlled means operating in the roadway for moving the cables to tilt the track sections.

2. A gate construction including gate posts supported at opposite sides of a roadway, track sections pivotally connected to the gate posts at points intermediate the ends of the track sections, gate sections movable on the track sections and adapted to gravitate to the lower ends of the track sections, an actuating lever supported above the track sections, means for imparting movement of the actuating lever to the track sections to tilt the track sections, operating cables connected with the lever for operating the lever, a treadle in the road surface and connected with the cables for moving the cables by the weight of a vehicle passing thereover.

In testimony that I claim the foregoing as my own, I have hereto affixed my signature.

DANIEL B. COATES.
